Specification for Design.

Patented Nov. 25, 1913.

Application filed October 3, 1910. Serial No. 585,152. Term of patent 7 years.

To all whom it may concern:

Be it known that I, OLIVER C. DENNIS, a citizen of the United States, residing at Chicago, in the county of Cook and State of Illinois, have invented a new, original, and ornamental Design for a Cigar and Ash Receiver, of which the following is a specification, reference being had to the accompanying drawing, forming part thereof.

The drawing is a perspective of a device embodying the new design.

The receiver is characterized by having a vertical back, an inclined top b, having an opening c therein for receiving the ashes and cigars, and triangular sides a, the back edge of which is vertical.

I claim:

The ornamental design for a cigar and ash receiver, as shown and described.

OLIVER C. DENNIS.
